UNITED STATES PATENT OFFICE.

MAX M. COHN, OF PIEDMONT, CALIFORNIA,

LOOSE-LEAF-PAPER DISPENSER AND CARTON-HOLDER.

1,148,757.

Specification of Letters Patent.

Patented Aug. 3, 1915.

Application filed October 7, 1914. Serial No. 865,481.

To all whom it may concern:

Be it known that I, MAX M. COHN, a citizen of the United States, residing at Piedmont, in the county of Alameda and 5 State of California, have invented new and useful Improvements in Loose-Leaf-Paper Dispensers and Carton-Holders, of which the following is a specification.

This invention relates to a device for containing and dispensing paper towels and such articles, and particularly to a holder for towels packed in cartons.

The object of my present invention is to provide a substantial, yet inexpensive, attractive container for cartons of packed, interfolded paper towels, and one adapted to be readily attached to a convenient support and from which the towels may be drawn rapidly and unmutilated.

20 Another object of this invention is to provide a container serviceable in either private or public institutions.

This device is especially useful with cartons of towels of the type disclosed in my 25 application for "Loose leaf dispenser", filed on or about the 18th day of August, 1914, Serial Number 857,316.

The invention consists of the parts and the construction and combination of parts 30 as hereinafter more fully described and claimed, having reference to the accompanying drawings, in which—

Figures 1 and 2 are perspective views showing one construction of the container. 35 Fig. 3 shows a modification of the invention, being the preferred type. Fig. 4 is a vertical section of the container without its cover.

The towels or other articles to be dispensed are represented at A. The carton is in the form of a thin rectangular tube of oblong cross-section, the front and back walls 2—3 having their central portions brought together at top and bottom, as 45 shown respectively at 4—5. At the lower portion of the front is made a horizontal slot 6 through which the towels are successively drawn.

The container comprises a bottom portion 50 7 having a pocket of sufficient length and width to receive the lower end of the carton; the front edge of the bottom registering with the lower edge of the withdrawal slot 6. The bottom has an upwardly extending back 8 perforated at 9 to permit of being hung or screwed to a suitable support.

The bottom portion 7 of the holder and the back 8 support a curved inclined bottom rest 10 for the corresponding wedge-like portion 5' of the carton and maintain the 60 carton and holder in proper relation so as to insure a proper feed of towels through the withdrawal slot. The upper end of the back 8 is bent over to form a hook 11 to receive and cover the connected upper edge 4 65 of the carton. Under some circumstances this hook may be dispensed with as the carton is usually stiff enough to stand alone in the holder.

When a loaded carton has been placed in 70 the bottom 7 and the latter hung up, the towels may be drawn out without danger of dislodging the carton from the holder and often this device is sufficient for practical purposes, especially for domestic use. If 75 the device is to be installed in a public establishment, however, for the dispensing of towels to the transient public, the carton is preferably concealed by a cover 12, having a front panel 13 which may be utilized as an 80 advertising space, or otherwise. The cover may or may not be closed at the back, since the back of the carton is concealed anyhow. It may be hinged to the bottom section 7, as shown at 14, Fig. 3, or it may be 85 loosely slipped over the carton and freely removable, as shown in Figs. 1 and 2. In any case a withdrawal slot 15 is formed which is adapted to register with the withdrawal slot 6 in the carton. Preferably this 90 slot 15 is formed by the respective co-operating bottom and top front edges of the cover 12 and bottom 7.

When the device is assembled, with a carton in place, a towel A is presented through 95 the registering openings 15 and 6 ready for withdrawal in the usual fashion. To recharge the holder it is only necessary to open or remove the cover, take out the emptied carton, and insert a fresh loaded 100 one, closing the cover and locking it, if desired.

Having thus described my invention, what I claim and desire to secure by Letters Patent is—

1. A holder for loose leaf containing cartons having withdrawal slots, consisting of a pocket which when the carton lower end engages therein has the top edge of its front wall disposed adjacent the slot, a back projecting upwardly from the pocket, and means borne by the back to engage the top 110

part of the carton to secure the latter to the holder.

2. A holder for loose leaf containing cartons having withdrawal slots consisting of a case composed of a lower receptacle adapted to receive the carton bottom and to allow the carton slot to be exposed above its top and a top part which has a lower portion that co-operates with the lower receptacle to form a withdrawal slot that registers with the carton slot.

3. A holder for loose leaf containing cartons having withdrawal slots consisting of a two-part case having portions which co-operate to form a slot that registers with the carton slot, one of the parts being adapted to inclose the top and the other the bottom of the carton.

4. A carton retainer consisting of a holder having a pocket and a back projecting above the pocket, means in the pocket which automatically upon the carton contacting therewith moves the latter against the pocket front, and means borne by the back to engage the upper end of the carton to support the said upper carton end so that the holder may be used with or without a cover.

5. A holder for loose leaf containing cartons that have inclined bottoms consisting of a receptacle, means in the receptacle to engage said carton bottom to automatically move and guide same toward and against the receptacle front and to sustain same against said front, and means secured to the back of the receptacle to engage the top of the carton to hold the latter against the back of the receptacle.

6. A carton retainer consisting of a holder with a pocket into which an end of the car-

ton may be placed and having an upwardly extending back, and means at the top of said back for engaging and supporting the top of the carton.

7. A holder for loose leaf containing cartons for use either with or without a cover consisting of a bottom receptacle having an elongated back for securement to a support and having a cover movably connected to the receptacle and to the upper end part of the back and means independent of the cover to support the carton in the pocket.

8. A holder for loose leaf containing cartons that have withdrawal slots consisting of a pair of telescopic upper and lower receptacles which co-operate to inclose the carton and which have free portions at their fronts that are spaced and conjointly form a slot in the front vertical face of the holder for register with the carton slot.

9. A holder for loose leaf containing cartons having withdrawal slots consisting of a bottom receptacle having an elongated vertical back and a cover having a front the lower edge of which is spaced above the top edge of the front side of the receptacle to form a slot adapted to register with the carton slot and having sides which engage with the ends of the receptacle and a top which connects with the upper end of said back.

In testimony whereof I have hereunto set my hand in the presence of two subscribing witnesses.

MAX M. COHN.
